UNITED STATES PATENT OFFICE.

CARYL D. HASKINS, OF SCHENECTADY, NEW YORK, ASSIGNOR TO GENERAL ELECTRIC COMPANY, A CORPORATION OF NEW YORK.

TIME-LIMIT CIRCUIT-CONTROLLER.

SPECIFICATION forming part of Letters Patent No. 727,624, dated May 12, 1903.

Application filed July 30, 1901. Serial No. 70,237. (No model.)

To all whom it may concern:

Be it known that I, CARYL D. HASKINS, a citizen of the United States, residing at Schenectady, in the county of Schenectady, State 5 of New York, have invented certain new and useful Improvements in Time-Limit Circuit-Controllers, (No. 2,036,) of which the following is a specification.

This invention relates to circuit-controllers 10 of that class in which a time interval is desired between the instant of an occurrence and the time at which an effect shall be produced on a controlled piece of apparatus. Such devices are employed, for example, in 15 governing the operation of circuit-breakers. It is desirable that circuit-breakers should not operate instantly on a small percentage of overload, as motors and other electric translating devices are not damaged by the con- 20 tinuance of a moderate overload for a short length of time, and it is desirable not to have the service interrupted by a brief overload due to some momentary fluctuation, provided the circuit-breaker may be safely tripped 25 within a time limit which would not endanger the safety of the generator or translating devices. Devices of this kind as commonly employed provide clockwork, the time-train being released by a magnet in the circuit in 30 case of an overload and after a determinate interval serving to trip the circuit-breaker. If, however, the overload should cease within such interval, the clockwork is so adjusted as not to trip the circuit-breaker and to stop 35 ready for another operation. With such apparatus, however, an uncertainty of operation results, as the operating parts are delicate and liable to get out of order from repeated use, from neglect of winding, and 40 other causes.

My invention contemplates the construction of a time-limit control device adjustable as to the time limit, not dependent upon clockwork, always ready for action, and of 45 great simplicity of construction.

In carrying out my invention I provide a reservoir for a liquid capable of being tilted or revolved on its bearings, so as to permit a flow of the liquid from one chamber of the 50 reservoir to another, the duct through which the flow is effected being of such character

as to require a definite and preferably adjustable time interval for a determinate-quantity transfer. By means of the flow the circuit to be controlled is effected so as to trip 55 the circuit-breaker or control the translating device of other character which is to be governed. I provide also means by which upon a predetermined maximum overload the control-circuit may be instantly affected so as to 60 guarantee the safety of the controlled apparatus against such highly-abnormal currents.

The simplest form in which I have thus far practiced the invention comprises a reservoir 65 provided with an adjustable counterweight containing two chambers connected by a communicating channel and mounted on trunnions, so as to be capable of tilting. One end is affected by an electromagnet in the govern- 70 ing-circuit, which serves to tilt the reservoir when an overload occurs. I place in the reservoir a body of conducting liquid—such, for example, as mercury—although other mobile material—such, for example, as conducting- 75 pellets—might be employed. When the electromagnet is energized, the reservoir is tilted and the conducting liquid flows from one chamber to the other, and after a definite amount has been transferred contacts con- 80 nected with the controlled circuit are completed, either directly by the conducting liquid or gravitatively by reason of the transfer of liquid. Moreover, by means of an adjustable device the level of the liquid may be al- 85 tered so as to vary the time in which the contacts are connected.

My invention may be applied either to direct or alternating currents.

The several features of novelty will be 90 hereinafter more particularly described and will be definitely indicated in the claims.

In the accompanying drawings, which illustrate the invention, Figure 1 is a side elevation of a device embodying my improvements 95 adapted for use with alternating currents. Fig. 2 is a similar device adapted for use with direct currents, and Fig. 3 is a sectional view showing the construction of the device.

I have shown it as formed in the shape of 100 an hour-glass, having two bulbs 12, connected by a neck which is perforated, so as to estab-

lish communication between the two bulbs, as seen in Fig. 3. One of the chambers may carry contacts, as 3 4, one at least of which should be insulated. The device is pivotally mounted, so as to rock in a vertical plane, as indicated, and carries an armature 5, co-operatively arranged to an electromagnet included in the controlled circuit. When used with alternating currents, this electromagnet should be laminated and the armature formed of a disk of good conducting material, such as copper. I prefer to employ in the reservoir a conducting liquid, such as mercury, though in some cases a non-conducting liquid may be employed and a float or other equivalent device be used to actuate the controlled circuit. The device is provided with an adjustable counterweight 6 to retract the apparatus to the normal horizontal position when the disturbing influence is removed. The communicating channel 7 between the two chambers should be of such a size as to require a determinate time interval for the transfer of sufficient quantity of fluid to affect the controlled circuit. As shown in the drawings, the contacts 3 4 are set on a diametrical vertical line, and when the apparatus is tilted under the influence of the electromagnet mercury will be transferred from the higher to the lower chamber and after a definite interval will bridge the contacts 3 4. One circuit-terminal may be mounted on the base, as indicated at 8, and the other be led to the contact-post 3. The terminals 8 and 3 may be included in a local circuit containing the trip-coil of the circuit-breaker or a cut-out device or other translating device to be operated. After the translating device has been operated the controlling-electromagnet 9 is deenergized, and the counterweight 6 restores the apparatus to its normal position. In case it is desired to have the circuit-breaker operated under two conditions of current—as, for example, a moderate overload lasting for a definite time or a definite maximum overload requiring immediate operation—the contact 8 may be made flexible and be co-operatively arranged to a companion contact 8^a, so that the strong influence exerted by the electromagnet will not only tilt the device to a position where it would trip the circuit-breaker after the lapse of a definite time, but will force it to a position which will close the contacts 8 8^a and immediately close the tripping-circuit.

The sensitiveness of the device may be varied by an adjustment of the counterweight 6 and the time interval varied by an adjustment of a displacement-screw 10. In order to render its action uniform, a pipe 11 is used to connect the two reservoirs above the liquid-level, thereby permitting a uniform

transfer of liquid by equalizing the air-pressure.

In the case of an alternating current the copper armature 5 is repelled on overload. The contact devices are therefore placed at the end remote from the magnet. With a direct current an iron armature may be placed at the same end, as indicated in Fig. 2. 70

The walls of the reservoir may be formed of any suitable material, such as porcelain or glass, or even metal.

Having thus described my invention, what I claim as new, and desire to secure by Letters Patent of the United States, is—

1. A circuit-controller comprising a pivoted liquid-reservoir containing two chambers connected by a duct, an operating-magnet to effect transfer of liquid from one chamber to the other upon a determinate current strength in the magnet-circuit, contacts in a controlled circuit closed by the transferred liquid after a determinate quantity has been transferred, and contacts closed instantly by the reservoir 85 when a predetermined maximum current flows through the magnet.

2. A time-limit circuit-controller comprising a pivoted liquid-reservoir containing two chambers connected by a duct, an operating-magnet to effect transfer of liquid from one chamber to another upon a determinate current strength in the magnet-circuit, a circuit controlled by a determinate amount of liquid transferred, and an adjustable counterweight 95 for varying the current strength to which the controller responds.

3. A circuit-controller comprising a pivoted liquid-reservoir containing two chambers connected by a duct, an operating-magnet to effect transfer of liquid from one chamber to the other upon a determinate current strength in the magnet-circuit, contacts in the controlled circuit closed by a determinate amount of liquid transferred, and an adjusting device 100 for altering the relation of the contacts to the liquid.

4. A circuit-controller comprising a pivoted liquid-reservoir containing two chambers connected by a duct, an operating-magnet to effect transfer of liquid from one chamber to the other upon a determinate current strength in the magnet-circuit, contacts in a controlled circuit closed by a determinate amount of liquid transferred, and adjustable means for 110 altering the free space in the contact-chamber to vary the time limit.

In witness whereof I have hereunto set my hand this 26th day of July, 1901.

CARYL D. HASKINS.
